UNITED STATES PATENT OFFICE

SAMUEL SOLOFF, OF BROOKLYN, NEW YORK

NECKTIE HOLDER

Application filed May 5, 1928. Serial No. 275,522.

This invention relates to improvements in necktie holders and has for its object provision for a necktie holder of compact form, which will be sufficient to accommodate the 5 average man's supply of neckties.

Further objects of the invention are the provision of a necktie holder adapted to be fastened to a wall to which the neckties may be affixed and from which the neckties may be 10 detached with a minimum of trouble and without touching any but the specific necktie wanted.

Other objects of this invention are the provision of a necktie holder attachable to a 15 wall, which will be compact in form, neat in appearance and economical to manufacture.

Further objects will be apparent from the specification and drawings in which

20 Fig. 1 is a perspective view of my complete holder.

Fig. 2 is a side view of my complete holder attached to a wall, showing also side views in section of the holder in two different positions.

25 Fig. 3 is a top plan view of my improved holder showing the view of the same attached partly in section.

Fig. 4 is a plan view of the single holding 30 unit on which the ties are arranged.

Fig. 5 is a perspective view of the same unit.

Fig. 6 is an enlarged view of the end of 35 the individual unit on which the ties are arranged, showing the construction and bifurcation of the end.

Fig. 7 is a sectional enlarged view of the 40 end of the separate unit shown in place and showing the manner in which the end of the bar is permanently held by the vertical side pieces of the holder.

The frame of the holder is made of two 45 flat bars of metal A and B, which are joined at the bottom by the nut and bolt C and D and at the top by the bolt E and the threaded thumb piece F. Between the members A and B at the top and passing through the bolt E, are the right angled fasteners G and H, which are fixed to the wall through the screws 50 K and K' by loosening the thumb piece F.

The body of the holder may be first shifted into any position as shown in Fig. 2 and then may be retained in that position by tightening the thumb piece F. This frictional adjustment is advantageous when ties are removed or replaced upon the holder and the construction shown enables this adjustment to be made with a minimum of labor.

At the bottom of the holder, I place a handle made of material similar to that of which the side pieces A and B are composed M, which is bolted to the frame of the holder by the threaded members P and P'. The individual units on which the ties are hung are illustrated fully in Figs. 4, 5, 6 and 7, 55 and may be stamped out of sheet metal or other material. The ends of these units Q are bifurcated and fit into openings in the frame of the holder and then are swaged into such openings as is shown in Fig. 7 of the drawing, so that such members, when once fixed into position, the end Q having been 60 enlarged by such swaging, cannot be removed from the frame and is permanently fixed 65 therein.

It should also be noted that these units are of a length so that the ends will protrude very slightly through the openings in the frame so that they can be satisfactorily swaged.

In this form of tie holder, any member 70 to keep the body of the holder away from the wall, is unnecessary, as the frame may be fixed in any position desired by means of the thumb screw F.

It will also be apparent that ties may be 75 replaced on the holder or detached therefrom by the arrangement shown without interfering with each other. The top of the tie, which impinges upon the holder, is not at any time in engagement or touching any other 80 tie.

Having fully described my invention, what I claim is:—

1. In a tie holder, the combination of a 85 rectangular frame made of two equal and opposite flat metallic members bolted together at their opposite ends, each of said opposite connections being adjustable, a swivel-bearing 90 at the top of said frame so that said tie holder may be moved to any desired position.

tion and a handle at the bottom of said tie holder by which the position of said tie holder may be regulated.

2. In a tie holder, a rectangular frame made of two equal and complementary flat metallic members, said members being adjustably connected to each other at both ends thereof, a swivel-bearing on the top of said tie holder so as to permit the movement of said tie holder to any desired position, a handle at the bottom of said tie holder for regulating such movement and a series of flattened bars held within said rectangular frame, said bars having pins thereon and integral therewith to act as spacers for the ties held in said holder.

In testimony whereof I affix my signature.

SAMUEL SOLOFF.
